ABSTRACT

Phosphorus-containing compounds are provided that impart excellent extreme pressure properties to lubricants.

8 Claims, No Drawings

PHOSPHOROUS-CONTAINING COMPOUNDS AND LUBRICANTS CONTAINING SAME

BACKGROUND OF THE INVENTION

1. Field of the Invention

The invention relates to a new class of phosphorus-containing compounds and to the use as lubricant additives. More particularly, it relates to compounds made by reacting certain anhydrides with phosphoramidates 10 as lubricant additives.

2. Discussion of the Prior Art

It is known that sliding or rubbing metal or other solid surfaces are subject to wear under conditions of extreme pressure. Wearing is particularly acute in modern engines in which high temperatures and contact pressures are prevalent. Under such conditions, severe erosion of metal surfaces can take place, even with lubricants of ever-increasing sophistication, unless a load carrying additive is present. As a consequence, much effort has been expended to discover additives useful in preventing such wear.

With certain metals, and under certain conditions, especially high temperature conditions, many of the conventional additives, although they may impart extreme pressure properties, may cause or permit corrosion of the metal. The compounds of this invention are not corrosive to metals such as copper.

SUMMARY OF THE INVENTION

In accordance with the invention, there are provided compounds of the formula

wherein R is a hydrocarbyl of from 1 to 40 carbon atoms and such R may be the same or different, X is halogen (e.g. chlorine, bromine, fluorine and iodine), Y is halogen, hydrogen or alkyl of from 1 to 10 carbon atoms, m is 1 to 4, n is 0 to 4 and p is 0 to 4. The invention also provides lubricant compositions comprising a lubricant and an extreme pressure amount of the compounds described.

As used herein, "hydrocarbyl" shall be understood to mean alkyl of 1 to 22 carbon atoms, cycloalkyl of 3 to 10 carbon atoms, aralkyl, aryl and alkaryl of 6 to 40 carbon atoms. It will be further understood that the R groups can be the same or different hydrocarbyls.

DESCRIPTION OF SPECIFIC EMBODIMENTS

In general the compounds are made by employing reactions well known in the art. That is they are formed by reacting an anhydride-containing compound with an amino-containing compound under conditions such that an imido structure is formed. Thus a polyhalopolycyclidicarboxylic anhydride and a phosphoramidate will react in the following manner to yield the indicated product.

R, X, m, n and p are as already defined. Further details of the process are available in U.S. Pat. No. 3,017,431 and CA 70, 288 (1969).

The reaction is preferably carried out in a non-polar solvent having a boiling point in the range of from about 80° C to about 200° C. The more preferred solvents are aromatic hydrocarbons boiling in the range of about 100°-120° C. The boiling range is not critical, however, and any suitably non-polar solvent can be used so long as it has a boiling point high enough to permit adequate temperatures of reaction and so long as it can be easily separated from the product.

Under proper conditions, the reaction will normally take from 4 to 14 hours, but conditions are preferably chosen so the product can be obtained in maximum yield in from 6-8 hours.

The additives of this invention can be used in a wide variety of lubricant media. Thus they are effective agents for lubricating oils such as mineral oils, both naphthenic and paraffinic, including those containing substantial amounts of aromatic oils. They are also effective for synthetic oils, such as synthetic hydrocarbons, which are obtained by polymerizing olefins, synthetic esters and for polysiloxanes and the like. The term "lubricant" also includes greases made from any of the mentioned lubricating oils by adding a grease forming agent thereto. One particular ester oil of importance is one made by reacting an aliphatic monocarboxylic acid containing from 4 to 10 carbon atoms, preferably 5 to 9, with pentaerythritol. A widely used lubricating oil is made from monopentaerythritol and a mixed C₈ and C₉ acid.

When used for the purposes herein disclosed, the additives are effective at from about 0.02% by weight to about 10.0% by weight, preferably from about 0.10% to about 2.0%.

The following examples will serve to illustrate the invention. It should be kept in mind that they are for illustration only and are not intended to limit the inventive scope. Parts are by weight unless otherwise indicated.

EXAMPLE 1

PART A

Preparation of di-n-butyl phosphoramidate.

Ammonia (37 g., 2.2 moles) was bubbled into a solution of di-n-butyl phosphonate (194 g., 1.0 mole) and carbon tetrachloride (154 g., 1.0 mole) in xylene (500

ml) while maintaining the temperature at 25° C with intermittent cooling in ice. The time required for the reaction was 3.5 hours. After removing ammonium chloride by filtration the solvents were removed by topping to a pot temperature of 100° C at 10 mm pressure. Fractional distillation of the residue yielded di-n-butyl phosphoramidate (bp 133°-139° C, 0.1 mm).

Product Analysis:

% Phosphorus — 15.7
% Nitrogen — 6.4

PART B

Preparation of 2-di-n-butyl-4,5,6,7,8,8-hexachloro-3a,4,7,7a-tetrahydro-4,7-methanonaphthalimide.

A mixture of 1,4,5,6,7,7-hexachloro-5-norbornene-2,3-dicarboxylic anhydride (94 g., 0.25 mole), di-n-butyl (52 g., 0.25 mole), and toluene (200 ml) were refluxed for seven hours under conditions for azeotropic removal of water. The product, 2-di-n-butoxy-phosphoryl-4,5,6,7,8,8-hexachloro-3a,4,7,7a-tetrahydro-4,7-methanonaphthalimide, was obtained after removal of the solvent and filtration through diatomaceous earth.

Product Analysis:

% Phosphorus — 5.5
% Chlorine — 38.1
% Nitrogen — 2.3

EXAMPLE 2

PART A

Preparation of dioleyl phosphoramidate.

In a manner similar to Example 1, Part A, dioleyl phosphoramidate was prepared from dioleyl phosphonate (279 g., 0.5 mole), carbon tetrachloride (154 g., 0.5 mole), xylene (500 ml) and ammonia (17 g., 1.0 mole).

Product Analysis:

% Phosphorus — 5.9
% Nitrogen — 2.2

PART B

Preparation of 2-dioleyoxyphosphoryl-4,5,6,7,8,8-hexachloro-3a,4,7,7a-tetrahydro-4,7-methanonaphthalimide.

In a manner similar to Example 1, Part B, 1,4,5,6,7,7-hexachloro-5-norbornene-2,3-dicarboxylic anhydride (74 g., 0.2 mole) was reacted with dioleyl phosphoramidate (115 g., 0.2 mole) in toluene (200 ml) to give the product.

Product Analysis:

% Phosphorus — 3.7

PRODUCT EVALUATION

LOAD-CARRYING TEST

The load-carrying capacity of a lubricant is measured under high speed shock conditions. The oil sample is placed in an SAE 1000 test machine as a lubricant for two steel test rings which are rotated against each other at different speeds, the faster at 1,000 rpm. Such rotation produces a combination of rolling and sliding actions. As rotation proceeds, the load holding the rings together is gradually increased by mechanical means until either the maximum load of the machine load is reached or until the rings seize, or fail to rotate. The maximum measurable loading for the machine used in

this test is 460 lbs. The results are reported in pounds at seizure.

Table 1 shows the improved load-carrying properties of the additives of the invention.

MODIFIED SAE TEST

Table 2 summarizes the results of a test described below.

10 The sample size used was 600 cc per run. The SAE extreme pressure lubricant testing machine was used in which two contra-rotating steel test rings (cups) turn at different speeds and roll and slide in line contact under controlled pressure. By the use of pulleys, the main shaft (upper) rotates at 156 rpm while the secondary (lower) shaft rotates at a lower speed that gives a slip ratio of 14.6:1.

15 Line contact pressure (load) is applied automatically at a constant rate of 7-8 lb (on the scale) per second.

An oil recirculation system pumps the oil from the heated oil reservoir through a heated oil line to the cradle containing the cups. The oil overflows from a port in the cradle and returns by gravity to the oil reservoir.

20 Two thermocouples, one in the reservoir and one in the oil delivery tube in the area of the test cups, help in controlling the temperature of the lubricant. The two thermocouples are connected with a temperature control system that regulates the heating. If desired, a simple temperature recorder can be connected to obtain a permanent record of the oil temperature through the test.

25 The test cups are cleaned, dried, weighed to the nearest milligram, and mounted on the two shafts. Check must be made of the alignment of the cups for proper contact and a runout of no more than 0.0005 in. Then the test oil, 600 cc, is poured in the oil reservoir and

30 heated with recirculation to 275 F. When the temperature of the oil in the delivery tube is stabilized at 275 F, ± 2 F, the break-in load of 20 lb scale (400 in.-lb) is applied and the machine is started. The break-in lasts 45 exactly 60 sec. After that, the load is gradually increased to 400 lb scale and stabilized there for 45 minutes.

35 If seizure occurs during break-in or during the load application, the machine is stopped and the oil is rated "fail-seizure." If the run is completed for the full 45 minutes, the cups are removed, cleaned, weighed to the nearest milligram, and examined for surface distress. If a seizure occurred, no weighing or further examination is necessary.

40 Table 3 shows the improved load carrying properties in the Shell Four-Ball Machine of a mineral oil containing additive amounts of the novel compounds described herein.

45 Table 4 shows the improved load-carrying properties in the Shell Four-Ball Machine of a synthetic oil containing additive amounts of the novel compounds described herein.

50 Table 5 illustrates the stability of these compounds in the Copper Corrosion Test, ASTM Method D130-6 (250° F, 3 hours).

TABLE 1

1000 SAE Load Carrying Test		
Additive	Conc., % P	Seizure Load
Base Oil	None	50
Example 1	0.15	310
Part B		
Example 2	0.15	400
Part B		

Base oil used was an SAE 90, solvent refined Mid-continent oil.

TABLE 2

156 SAE Wear Test		
Additive	Conc., % P	Wear (mg.)
Base Oil	None	Fail at 160 lbs.
Example 1	0.15	32
Part B		
Example 2	0.15	10
Part B		

Base oil used was an SAE 90, solvent refined Mid-continent oil.

TABLE 3
